TEXTILE BOBBIN SUPPORT

Joseph Annecq, Renaix, Belgium

Application January 21, 1950, Serial No. 139,840

Claims priority, application Belgium July 4, 1949

8 Claims. (Cl. 68—198)

1

This invention relates to a new type of support for textile bobbins. More particularly, it deals with a support for bobbins wound with yarns of textile fibers such as cheeses, cakes, cones, cops, spools, etc. which supports prevent the deformation of axially compressed columns of such cakes or cheeses mounted on spindles during fluid treatment of said cakes or cheeses, such as washing, dyeing, etc.

Previously, perforated disks and tubes have been employed for spacing yarn wound bobbins on spindles for their fluid treatment, but this type of supports easily become twisted and broken which causes ununiform penetration of the treating fluid through the fibers in the column, resulting in bad treating or dyeing.

Also specially designed plastic supports have been used but they dissolve in caustic treating solutions and are not resistant to hot solutions or to dyes, and therefore must be replaced periodically.

It is an object of this invention to produce a simple, effective, efficient and economic textile bobbin support which avoids all the disadvantages above mentioned.

Another object is to produce a bobbin support which is non-corrosive, can be used for a longer period of time, permits the treating fluid to pass easier and more uniformly through all the fibers of the yarn wound on the bobbins, enables longer columns of cheeses or cakes to be employed during the treating, and prevents leaking of the treating fluids between adjacent cheeses or cakes in a column.

In accordance with this invention, the support for bobbins strung on a spindle is made from a non-corrosive metal such as stainless steel, or the like, and comprises (1) an annular ring with a peripheral flange which supports the cylindrical end of a bobbin; (2) a cylindrical collar or sleeve which slides over the spindle upon which the bobbins are to be strung; and (3) a plurality of radial spokes between said ring and said collar which maintain them in spaced parallel planes and hold the end of the bobbin in said ring. Thus, each end of a cylindrical bobbin is fitted into the ring flange of such a support, and for adjacent bobbins, that is, those not at the ends of the columns but those which have two supports on adjacent ends of said aligned bobbins abutting each other, preferably have their abutting rings welded together to form a unit pair of opposed supports, the weld being continuous and preventing the treating fluids from passing between the two adjacent rings and likewise

from between adjacent bobbins of yarn in the column.

In the case of cakes, which have parallel wound threads on bobbins as distinguished from bobbins which have crossed wound threads on bobbins, the supports may be provided with additional annular rings with flanges to form annular troughs of sufficient diameter to fit over the whole ends of the cakes and thereby better prevent their deformation in the column.

The above mentioned and other features and objects of this invention and the manner of attaining them will become more apparent and the invention itself will be best understood by reference to the following description of specific embodiments of the invention taken in conjunction with the accompanying drawing, wherein:

Fig. 1 is the partial vertical section of a column of cheeses mounted on a spindle before they are compressed, the bobbins of which cheeses are fitted with the supports of this invention;

Fig. 2 is similar to Fig. 1 with the cheeses compressed on said spindle;

Fig. 3 is a vertical section of a unit pair of bobbin supports of the type shown in Figs. 1 and 2;

Fig. 4 is an axial or end view of the bobbin support shown in Fig. 3; and

Fig. 5 is a partial vertical section of a modified form of a bobbin support having an additional annular ring for supporting the whole end of a cake of yarn.

Referring to Figs. 1 and 2, there is shown how a column of cheeses 10 of yarn wound on porous cylindrical bobbins 11 may be strung on a spindle 12 and held in position on said spindle by means of the metallic supports 20 of this invention. The ends of the spindle 12 may be threaded to receive nuts 13 and 14. Near one end of the spindle 12 there may be provided a shoulder 15 which may be inserted through a larger hole 17 in a hollow conduit 16 and then clamped in a smaller hole in the opposite side wall of said conduit by the nut 14. The aperture 17 is sufficiently large to permit a treating fluid from the conduit 16 to pass through it and around the spindle 12 and up the center of the column of cheeses inside the bobbins, and between the spokes 21 of the supports 20. Thus a treating fluid, such as dye, may be forced under pressure from conduit 16 through the porous walls of the bobbins 11 to penetrate the fibers of the yarn of the cheeses 10 when said cheeses are compressed on the spindle 12 between the flat rigid disk 18, and the outer wall of the conduit 16

by the nut 13 as shown in Fig. 2. The supports 20 are not so long axially that they cannot permit axial compression of the cheeses, as is indicated by the space 19 in Fig. 1 between adjacent collars 22 of adjacent supports, as compared to the absence of this space in Fig. 2.

Each support 20, see Figs. 3 and 4, comprises an annular ring 23 with an outer peripheral flange 24 parallel to the axis of the ring, producing an L-shaped radial cross-section for the ring. It is within the flange 24 and on this ring 23 that the end of a bobbin fits, as shown in Figs. 1 and 2. Above the ring 23 in the direction of the flange 24 there is a cylindrical collar, hub, boss or sleeve 22 having a central aperture slightly larger than the outside diameter of the spindle 12, so that it may be easily slipped over the spindle and slid along said spindle without friction. To this sleeve type collar 22 there may be attached, or made integral therewith, equally spaced flat spokes 21 (four shown) which extend axially and radially outwardly from the collar 22 to the ring 23 at which they are bent at right angles to the axis of the collar in the plane of the ring 23 and there integrally attached, such as by electric welding, brazing, or soldering, to the surface of the ring 23 to form an integral piece or support. The spokes also, adjacent the ring 23 may project up parallel to the flange 24 for at least a short distance as indicated at 26 to engage the inside of the bobbins and center the support on the bobbins, thus forming a type of semi-trough for the ends of the bobbins.

Except for the supports at the two ends of the column, the intermediate adjacent pairs of supports, wherein the backs of two rings 23 are touching each other, may be and preferably are welded or soldered together at 25 to form a unit or integral pair as shown in Fig. 3.

In Fig. 5 is shown a modified form of bobbin support 30, in a unit pair, each support 30 comprising the same parts as in the support 20, namely, an annular ring 33, a flange 34, an axially spaced collar 32, and flat spokes 31 joining the collar with the ring 33, but the spokes are shown having a stepped configuration as distinguished from the angular or diagonally extending spokes 21 for the supports 20. In addition there is shown in Fig. 5 a second annular ring 35 having the same inside diameter as the ring 33 but having a greater outside diameter, at the outer periphery of which is also provided an axially extending flange 36, parallel to flange 34 and forming an annular trough 37 with flange 34 into which trough the whole end of a cake of parallelly wound yarn may be inserted, while its bobbin fits inside the inner flange 34 as described for support 20. In order to form an integral unit the adjacent second annular rings 35 may be welded or soldered to the ring 33 as shown, and in order to form a unit pair, two adjacent rings 35 may have the bottoms of their troughs 37 also welded or soldered together to prevent any fluid from passing between them when they are mounted in a column for treating.

The construction of the supports of this invention are simple and cheap in that they may be punched out of sheet material and bent into shape and welded together quickly and in large quantities. The flat spokes thus have a certain degree of resiliency which permits flexing without damage in the event the compression is continued between two adjacent pairs which have their collars in contact as shown in Fig. 2. The

fabrication of these supports from non-oxidizable or non-corrosive sheet metal, increases their life when used in solutions which corrode other materials. The comparatively large quadrants or sectors of space between the spokes materially increase the freedom of passage of fluid between the supports, which space did not exist when the supports were made of plastic having sufficiently thick walls to withstand the use to which they must be put as seen in my copending U. S. application, Serial Number 661,148, filed April 10, 1946 and now abandoned. Also, if desired, the stepped type of spokes shown in Fig. 5, may be substituted for the diagonally extending spokes 21 shown for the bobbin support in Fig. 3, and vice versa, without departing from the scope of this invention.

While there is described above the principles of this invention in connection with specific apparatus, it is to be clearly understood that this description is made only by way of example and not as a limitation to the scope of this invention.

What is claimed is:

- 25 1. A support for a textile bobbin comprising: an annular ring plate means having its outer peripheral edge turned up at right angles to the plane of said ring forming a cylindrical flange, a cylindrical sleeve of lesser outside diameter than the inside diameter of said ring positioned with respect to said ring so that the axes of said ring and said sleeve are aligned and said sleeve is spaced from said ring in the direction of and beyond said flange, said sleeve having a plurality of strips of equal length extending radially and axially from the end of said sleeve adjacent said ring, the outer ends of said strips being bent radially outwardly at right angles from said axis, and said bent ends being attached to said ring in its plane, whereby said strips form spokes between said sleeve and said ring to maintain said ring and sleeve in their relative position and to freely permit a fluid to pass through said ring and between said spokes.
- 30 2. The support of claim 1 wherein said strips extend substantially directly from said sleeve to said ring.
- 35 3. The support of claim 1 wherein said strips extend radially and then axially from said sleeve to said ring.
- 40 4. A support according to claim 1 wherein said plate means includes an additional cylindrical flange extending from said plane of said plate means between said peripheral cylindrical flange and said bent ends, said additional cylindrical flange being concentric with said peripheral cylindrical flange and extending from said plane in the same direction as said peripheral cylindrical flange.
- 45 5. A support for a pair of adjacent similar textile bobbins comprising: an annular ring having a cylindrical flange around its outer periphery, said flange extending axially of said ring on both sides of the plane of said ring, a pair of similar cylindrical sleeves along said axis of said ring spaced on each side of said ring beyond the ends of said flange, the outside diameter of said sleeves being less than the inside diameter of said ring, and a plurality of spokes extending from the end of each sleeve adjacent said ring to the inner diameter of said ring, whereby said sleeves are maintained in their relative position to said ring and fluid may freely pass through said ring and between said spokes.
- 50 6. In a column of porous bobbins adapted to

be wound with textile fibers and mounted on a spindle having a diameter smaller than the inside diameter of said bobbins around and along which spindle said bobbins are strung to form said column, and having bobbin supports located at each end of each bobbin for maintaining said bobbins uniformly spaced along and around said spindle, each said support comprising: an annular plate with a flange extending perpendicular to said plate in one axial direction around the outer diameter thereof, inside of which flange the end of a bobbin is adapted to fit, a cylindrical sleeve axial with and spaced from said plate which sleeve is adapted to fit around said spindle and which has an outside diameter less than the inside diameter of said annular plate, and a plurality of equal length spokes extending from the inside diameter of said plate to the adjacent end of said sleeve and at said plate being bent at right angles to said plate adapted to fit around the inside of said end of said bobbin, whereby said sleeve is maintained inside a bobbin and axial with said plate, and the end of said sleeve remote from said plate is adapted to be spaced from said plate less than half the axial length of a bobbin to permit axial compression of said column of bobbins, and whereby fluid may freely flow through the center of said column between said spokes inside said bobbins and around said spindle.

7. A support for a textile bobbin comprising: an annular ring plate means having around its outer peripheral edge a cylindrical flange projecting at right angles to the plane of said ring on both sides of said ring, a pair of cylindrical sleeves of lesser outside diameter than the inside diameter of said ring positioned with respect to said ring so that the axis of said ring and said sleeves

are aligned and one of said sleeves is spaced from said ring on each side of said ring beyond said flange, each of said sleeves having a plurality of strips of equal length extending radially and axially from the end of said sleeves adjacent said ring, the outer ends of said strips being bent radially outwardly at right angles from said axis, and said bent ends being attached to said ring to maintain said ring and sleeves in their relative position and to freely permit a fluid to pass through said ring and between said spokes.

8. A support according to claim 7 wherein said ring plate means includes additional cylindrical flanges extending from said plane of said ring on both sides of said ring between said peripheral outer cylindrical flange and said bent ends, said additional cylindrical flanges being concentric with said peripheral cylindrical flange.
